UNITED STATES PATENT OFFICE.

PAUL CONRAD, OF CHICAGO, ILLINOIS.

STOPPER OR CLOSURE FOR BOTTLES AND THE LIKE.

No. 889,872.

Specification of Letters Patent.

Patented June 2, 1908.

Application filed May 23, 1907. Serial No. 375,270.

To all whom it may concern:

Be it known that I, PAUL CONRAD, a subject of the Emperor of Germany, and a resident of the city of Chicago, county of Cook, 5 and State of Illinois, have invented certain new and useful Improvements in Stoppers or Closures for Bottles and the Like; and I do hereby declare that the following is a full, clear, and exact description of the same, reference being had to the accompanying drawings, and to the letters of reference marked thereon, which form a part of this specification.

Heretofore the stoppers or closures for 15 bottles containing beverages, etc., frequently consist of a metal cap piece into which is fitted a tin foil blank, then a thin cork and lastly a thin sheet of paper is secured over the cork which is in contact with the liquid 20 in the bottle. The flange of the cap fits without the mouth of the bottle and is pressed or crimped in place with its lower edge beneath the bead on the bottle by use of a suitable tool. Such stoppers are 25 necessarily expensive, consisting as they usually do of a multiplicity of parts and requiring great care in securing the same in place owing to the fact that such caps constructed of rigid metal require great pressure 30 to securely engage them to conform with the mouth of the bottle and afford an impervious joint for leakage deteriorates the value of any and with most entirely ruins the contents of the bottles.

35 It is an object of this invention to provide a resilient closure of the class described adapted to be easily pressed into the mouth of the bottle and which by its resiliency is firmly engaged in place affording an imper- 40

vious joint. It is also an object of this invention to eliminate the use of certain parts heretofore used and to provide a stopper which need not be fitted with exactness but which when 45 engaged in place entirely closes the mouth of the bottle and conforms thereto and locks itself in place affording a seal both within and outside the bottle providing a double seal.

The invention consists in the matters here- 50 inafter described and more fully pointed out and defined in the appended claims.

In the drawings: Figure 1 is a vertical section of a device embodying my invention showing the same in place in the mouth of 55 the bottle before sealing. Fig. 2 is a view similar to Fig. 1 showing the bottle sealed

and with the flange crimped beneath the bead. Fig. 3 is a bottom plan view of the stopper or closure. Fig. 4 is a top plan view thereof. Fig. 5 is an enlarged vertical section of the stopper illustrating the position assumed before insertion into the mouth of the bottle.

As shown in the drawings: A indicates the stopper or closure which may be made out of 60 any suitable metal to provide resiliency such as tinned sheet steel or other metal having an inner layer of thin block tin a provided on one side thereof either as a coating by any of the well known processes, or as a separate 65 sheet. Said stopper is formed by means of a suitable die or otherwise to afford a peripheral downturned outer flange a' of any suitable length and an inner downturned portion a^2 equal in length to the outer flange afford- 70 ing an annular channel therebetween into which fits the outer end of the neck of the bottle to a depth coincident to the width of the bead. A horizontal portion a^3 , integrally 75 connects said flange a' , and portion a^2 , and 80 integral with the lower edge of the inner portion a^2 is a resilient upwardly convex or conical head portion a^4 , which normally forces the portion a^2 yieldingly toward the flange a' , but which yields upwardly when pressure 85 is applied between said flange a' and portion a^2 thus permitting the rim of the bottle to fit accurately therebetween as shown in Fig. 1. A thin ring of cork B is secured beneath the transverse portion a^3 below which may be a 90 layer of pure tin foil if desired.

In applying the cap or closure, it is pressed firmly upon the neck of the bottle and the central convex head is pressed inwardly flattening the same somewhat as the outer 95 flange is crimped beneath the bead c at the mouth of the bottle thus firmly engaging the bottle neck within and also beneath the bead firmly locking the closure in place and molding the soft inner layer to the surface of the 100 bottle to perfectly seal the same.

The operation is as follows: In manufac- 105 turing, the width of the annular space between the flange a' and portion a is slightly less than the rim at the mouth of the bottle and the central portion a^4 is slightly conical or convex as shown in Fig. 5. It is thus seen 110 that by simply pressing the stopper into position the same conforms to the mouth of the bottle and also that the central portion con- tinuously exerts tension to afford an imper- vious seal.

While I have shown the portions connected by means of curved lines yet obviously the stopper may be constructed with angular connection and also if preferred a sheet of 5 tin foil may be used beneath the stopper in lieu of the cork or in combination therewith in either case the resilient portion clamps the flange a' and portion a^2 tightly against the bottle.

10 Details may be varied as for instance the annular channel may be made sufficiently wide to receive the rim at the mouth of the bottle therein and the central portion greatly convexed and when the stopper is pressed in 15 place this central portion is forced downwardly to force the portion a^2 outwardly and thus draw the flange inwardly to afford a double seal and in either case the seal is effectively made. I therefore do not desire 20 to limit this application as to details as many changes may be made without departing from the principles of this invention.

I claim as my invention:

1. A bottle closure or stopper affording an 25 inner and an outer seal and having a convex portion adapted to yield upwardly.

2. A stopper or closure having a portion to seal against the rim of the neck of a bottle both inside and outside thereof, a central 30 conical upwardly yielding portion and a lining covering the entire inner face of the closure.

3. A device of the class described having 35 parallel portions affording a channel therebetween and a resilient portion forcing the parallel portions oppositely to clamp the neck of a bottle therebetween.

4. A bottle seal or closure having a channel 40 to receive the top of the neck of the bottle therein and resilient means adapted to clamp the closure to conform to the neck of the bottle and affording a double seal for said bottle.

5. A closure or stopper comprising an 45 outer downturned flange, an inner parallel portion, a transverse portion connecting the same at corresponding edges and a resilient portion integral with the inner portion acting to force said flange and parallel portion to firmly seal against the outside and inside of 50 the neck of the bottle respectively.

6. A closure or stopper comprising an inner and an outer portion to fit within and outside the rim of the neck of the bottle, a transverse integral portion, a convex central 55 portion adapted to fit in the mouth of the bottle and a lining for said stopper.

7. In a device of the class described the combination with a bottle having a bead thereon of a closure or stopper therefor having 60 a flange to fit without the neck and a portion to fit within the neck affording a channel

therebetween a ring of suitable material secured at the base of the channel, and a conical resilient portion adapted to press the flange and first named portion toward each other.

8. A resilient stopper or closure having portions affording a double seal and a central portion integral with one of the sealing portions adapted to exert a pressure at all times 70 on the sealing portions.

9. A bottle seal embracing a closure having an outer flange, a portion parallel therewith providing a space therebetween of less width than the thickness of the neck of the 75 bottle to which applied and a portion integral with said parallel portion adapted to yield upwardly as the closure is applied.

10. A closure embracing parallel connected portions adapted to yield oppositely and a 80 portion integral with one of the parallel portions adapted to yield upwardly as the parallel portions yield oppositely.

11. A closure embracing parallel connected portions adapted to clamp within and 85 outside the neck of the bottle, a portion adapted to yield upwardly as the closure is applied to the object sealed and at all times exerting pressure to force the portions against the bottle and a lining for said closure conforming to the inner surface of the 90 closure.

12. A bottle closure embracing parallel portions integrally connected at their corresponding ends, and affording a downwardly 95 opening passage therebetween, a portion integral with the inner parallel portion adapted to yield to permit said parallel portions to be forced apart and a separate lining for the inner surface of the closure.

13. A bottle closure embracing portions for engaging within and without the neck at the mouth of the bottle, a central portion exerting pressure to resist placing the closure in position and for forcing the inner 105 portion against the neck of the bottle when in position and a lining of block tin or suitable material for the closure.

14. A closure embracing parts fitting within and outside the bottle, a yielding portion 110 integral with one of said parts adapted at all times to jam said parts firmly against the inside and outside of the neck of the bottle affording an impervious seal and a lining on the inner side of the closure.

In testimony whereof, I have hereunto subscribed my name in the presence of two subscribing witnesses.

PAUL CONRAD.
